United States Patent Office.

RICHARD FLYNN, OF WEST BROOKFIELD, MASSACHUSETTS.

Letters Patent No. 79,966, dated July 14, 1868.

IMPROVED STEAK-MASHER.

The Schedule referred to in these Letters Patent and making part of the same.

KNOW ALL MEN BY THESE PRESENTS:

That I, RICHARD FLYNN, of West Brookfield, in the county of Worcester, and Commonwealth of Massachusetts, have invented certain new and useful Improvements in Steak-Mashers; and I do hereby declare that the following is a full, clear, and exact description of the same, reference being had to the accompanying drawings, forming a part of this specification, in which—

Figure 1 represents a front view of my improved steak-masher, and

Figure 2 represents a section on line A B, fig. 1.

To enable those skilled in the art to which my invention belongs to make and use the same, I will proceed to describe it more in detail.

In the drawings, A A are the steak-mashing rolls, the journals of which are supported in suitable bearings fitted in slots α in the end pieces B B, which are fastened at the bottom to the base-piece C; and are united at the top by a cross-piece, D.

The rolls A A are provided from end to end with spiral-screw grooves b, which run around the peripheries of the rolls a little obliquely to axis of motion of said rolls. The spiral grooves b are cut or intersected by parallel V-shaped grooves, c. The spirals, b, of each roll run in the same direction, as shown in the drawings, for the purpose hereinafter mentioned.

The journals of the upper rolls are supported in boxes, which rest upon springs d, while the said boxes are forced down by the curved spring E, the ends of which rest upon the boxes or bearings of the journals of the top roll, while said spring is forced down by a thumb-screw, F, which passes through the cross-piece D, as fully indicated in fig. 1.

The journals G G of rolls A A are provided with gears H H, which mesh in with each other. A hand-crank, I, is attached to the end of the journal of the bottom roll.

The operation is as follows: The operator standing in front of the machine, by means of the crank I turns the steak-mashing rolls A A, so as to have the lower surface of the lower roll and the upper surface of the upper roll turn towards him. The steak being entered or fed in between the rolls, is carried through and mashed by the peculiar-shaped surface of the rolls A A, whereby it is rendered very tender when properly cooked and prepared for the table.

The operation of mashing by the peculiarly-shaped surface of the rolls, causes the steak to be partially rolled laterally, both at top and bottom, as it is fed through the rolls, thereby preventing, in a great measure, the escape of the juices of the meat.

It will be observed that the action of the top roll tends to roll the steak in one direction, while the lower roll tends to roll it in the opposite direction, thus rolling and twisting the fibres of the meat at the same time they are mashed.

As soon as the thumb-screw F is loosened, the springs d elevate the upper roll; the space between the rolls can therefore be increased or contracted at pleasure.

Having described my improved steak-masher, what I claim therein as new, and of my invention, and desire to secure by Letters Patent, is—

The employment, in a steak-mashing machine, of the rolls A A, the teeth of which are arranged so as to form a continuous spiral from one end to the other of each roll, the said rolls being geared together so as to move in opposite directions, while their spirals run in the same direction, as shown and set forth.

Witnesses:

W.M. A. PATRICK,

Jos. F. HITCHCOOK.

RICHARD FLYNN.
